(57) **CLAIM**

The ornamental design for a chair with utility holders as shown and described.

DESCRIPTION

FIG. 1: is a perspective view of a chair with utility holders in an extended position;

FIG. 2: is a perspective view of a chair with utility holders in a retracted position;

FIG. 3: is a front view of a chair with utility holders in an extended position;

FIG. 4: is a back side view of a chair with utility holders in an extended position;

FIG. 5: is a right side view of a chair with utility holders in an extended position;

FIG. 6: is a left side view of a chair with utility holders in an extended position;

FIG. 7: is a top view of a chair with utility holders in an extended position;

FIG. 8: is a bottom view of a chair with utility holders in an extended position;

FIG. 9: is a perspective view of a chair with utility holders in an extended position showing environmental matter in broken lines;

FIG. 10: is an isolated perspective view of the right arm of a chair with a utility holder in an extended position;

FIG. 11: is an isolated perspective view of the right arm of a chair with a utility holder in a retracted position;

FIG. 12: is an isolated front view of the right arm of a chair with a utility holder in an extended position;

FIG. 13: is an isolated back view of the right arm of a chair with a utility holder in an extended position;

FIG. 14: is an isolated right side view of the right arm of a chair with a utility holder in an extended position;

FIG. 15: is an isolated left side view of the right arm of a chair with a utility holder in an extended position;

FIG. 16: is an isolated top view of the right arm of a chair with a utility holder in an extended position;

(Continued)

FIG. 17: is an isolated bottom view of the right arm of a chair with a utility holder in an extended position;
 FIG. 18: is an isolated perspective view of the left arm of a chair with a utility holder in an extended position;
 FIG. 19: is an isolated perspective view of the left arm of a chair with a utility holder in a retracted position;
 FIG. 20: is an isolated front view of the left arm of a chair with a utility holder in an extended position;
 FIG. 21: is an isolated front view of the left arm of a chair with a utility holder in an extended position;
 FIG. 22: is an isolated right side view of the left arm of a chair with a utility holder in an extended position;
 FIG. 23: is an isolated left side view of the left arm of a chair with a utility holder in an extended position;
 FIG. 24: is an isolated top view of the left arm of a chair with a utility holder in an extended position; and,
 FIG. 25: is an isolated bottom view of the left arm of a chair with a utility holder in an extended position.
 FIGS. 10-25, showing portions of the chair as enlarged and isolated from the remainder of the chair, are included for clarity of illustration.

The broken lines showing portions of the chair with utility holders form no part of the claimed design. The broken lines showing environmental subject matter in FIG. 9 form no part of the claimed design.

1 Claim, 15 Drawing Sheets
